WINDOW OPERATOR

Charles Jansen, Brooklyn, N. Y., assignor to
Nelson J. Edge, Jersey City, N. J.

Application September 25, 1948, Serial No. 51,170

9 Claims. (Cl. 268—116)

1

The present invention comprises improvements over the inventions disclosed in my copending application, Serial No. 581,604, filed March 8, 1945, for Window Construction. In the construction there disclosed, a window of the type comprising a plurality of panes pivoted on substantially horizontal axes is provided with means operated by a single motion of an operating lever, for first closing the panes and then actuating a combined weatherstrip and locking bar into a groove in the window frame, reverse motion of the operating handle being effective to first disengage the weatherstrip from its groove and then to open the panes.

An object of the present invention is to provide improved weatherstrip and locking means.

Another object is to provide a pane unit constituting a light of the window.

Another object is to provide improved frames for the individual pane units of the window.

Another object is to provide a simplified and improved tilting and locking mechanism.

Still another object is to provide improved actuating means for the tilting and locking mechanism.

Another and further object is the provision of automatically reversible and automatically locking mechanism for the actuating means of the tilting and locking mechanism.

In accomplishing the objects of the present invention, improved weatherstrip means are provided in the form of a weatherstrip lip formed integral with the stile member and extending into the window opening beyond the plane of the jamb surface, the latter having a groove along the base of the lip, in which groove a resilient body such as sponge rubber is located. The weatherstrip and locking function will be described in connection with the description of the sash member.

In the pane unit of the sash member, channel members are provided for mounting two panes of glass in parallel spaced relation, and trunnion members are provided comprising integrally trunnions and channels adapted to support the pane unit in operative relation to the window frame. These channels extend for the entire height of the pane units and for a short distance across the bottom thereof and have axial movement which is effective at one limit to seal and lock the pane and at the other limit to unseal and unlock the pane and permit tilting thereof.

Tilting and locking mechanism operative upon the trunnion members is provided in the form of a bifurcated rocker arm pivotally mounted up-

2

on the trunnion and axially fixed relative to the frame. The rocker arm is formed with a diagonal slot into which extends a pin mounted radially in the trunnion. Rocking of the rocker arm first causes axial movement of the trunnion to unseal and unlock the pane, then rotation thereof to tilt the pane. Reverse motion first causes the pane to return to vertical position and then draws the trunnion into sealing and locking relation with the window frame.

Actuating means for the rocker arm are provided comprising a rocker bar connected to all the rocker arms in one stile of the window frame. A gang of pulleys is mounted on the lower end 15 of the bar, and another gang is mounted in the lower corner of the frame. A cable is led around the two gangs of pulleys and to a ratchet mounted in the window sill. Another cable is connected to the upper end of the rocker bar and over pulleys 20 to another ratchet.

The two ratchets are mounted on the main shaft of the window, said shaft extending transversely of the sill. A pin extending radially from said shaft extends into a diagonal slot in a sleeve 25 mounted on the shaft. Said sleeve comprises preferably integrally, pins extending radially and in opposite directions therefrom and into recesses in either of the ratchets. Rotation of the main shaft first causes axial travel of the sleeve 30 to move its pins from engagement with one ratchet into engagement with the other ratchet, and then causes rotation of the last mentioned ratchet.

A double pawl is pivotally mounted in operative relation to both ratchets, having two arms, each positioned to engage the teeth of one ratchet to prevent rotation thereof in one direction, the teeth of the ratchets facing in opposite directions and the pawl being so shaped and mounted 35 that in a position of rest it locks against reverse motion the ratchet which opens the panes, being out of engagement with the other ratchet. The pawl may be manually moved by a handle extending through the sill so as to disengage the opening ratchet and lock against reverse motion the ratchet which closes the panes and seals and locks them in closed position.

Beginning with the window closed and locked, 40 a slight counterclockwise actuation of the main shaft is first necessary, whereupon the pawl will by gravity fall out of engagement with the locking ratchet. Clockwise rotation of the main shaft will then kick the sleeve axially, disengaging the pins from the locking ratchet and en-

gaging them with the opening ratchet. Rotation of the latter winds the cable connected thereto, drawing down the rocker bar and arms, kicking the trunnions and channels out of locking engagement with the frame and then rotating the trunnion members to tilt and thereby open the panes. The opening of the window may be halted at any point and the pawl in engagement with the opening ratchet will prevent closing. It is understood that in windows of the general type in which the panes are mounted for tilting on horizontal axes, said axes are usually above the center of gravity of the pane so that each pane tends to close by gravity.

To partially close the window, a slight clockwise motion of the main shaft is necessary to permit manual disengagement of the pawl, while counterclockwise motion of the main shaft permits gravity closing of the panes to the desired degree, when the pawl being released reengages the opening ratchet to prevent further closing.

To close and lock the window, the pawl having been disengaged from the opening ratchet as described above, counterclockwise motion of the main shaft permits the panes to assume vertical, closed position. Further counterclockwise motion kicks the sleeve so that its pins engage the closing ratchet, which pulls the rocker bar and arms upwards, first tightening the panes against one another and then kicking the trunnion pin toward the frame, thus drawing the trunnion members in the same direction, so that they pass to the rear of the weatherstrip lip of the frame, being substantially in parallel contact therewith to seal and lock the window. With the locking cable still under tension the pawl is manually actuated into engagement with the locking ratchet and will remain so engaged until released by further clockwise motion of the main shaft.

Other objects of this invention will in part be obvious and in part hereinafter pointed out. The invention accordingly consists in the features of construction, combination of elements, and arrangements of parts which will be exemplified in the constructions hereinafter described. In the accompanying drawing in which is shown one of the various possible illustrative embodiments of this invention:

Figure 1 is a front elevational view of my improved window, partly in section.

Figure 2 is a section on the line 2—2 of Figure 1.

Figures 3 and 4 are sections on the lines 3—3 and 4—4 of Figure 2.

Figure 5 is a section on the line 5—5 of Figure 4.

Figure 6 is a section on the line 6—6 of Figure 5.

Figure 7 is a fragmentary exploded view of the main shaft and ratchet assembly.

Figure 7A is a front elevational view of a pin disk.

Figure 8 is a section on the lines 8—8 of Figures 1 and 10.

Figure 9 is a section on the line 9—9 of Figures 1 and 10.

Figure 10 is a section on the line 10—10 of Figure 9.

Figure 11 is a section on the line 11—11 of Figure 9.

Figure 12 is a side elevation of the rocker bar connecting pin.

Figure 13 is a section on the line 13—13 of Figure 1.

Figure 14 is a corresponding view of the trunnion members only of Figure 13.

Figure 15 is a top elevational view of a trunnion member.

Figure 16 is a front elevation thereof.

Figure 17 is a detail of a lower corner of a pane unit.

Figure 18 is a section on line 18—18 of Figure 17.

Figure 19 is a fragmentary end elevation of a pane unit.

Figure 20 is a side elevation of the vertical molding of the pane unit.

Figure 21 is a front elevation thereof.

Referring now in detail to the drawings, a window frame 30 is illustrated as comprising the hollow metal stile members 31, 32, and hollow lintel and sill members 33, 34, respectively. Window sash 35, 36, 37, 38, 39 are titlably mounted in frame 30 for rotation about substantially horizontal axes each located above the center of gravity of its sash, so that the sash tends to assume a vertical, closed position by gravity.

The sash 35—39 are constituted by pane units 40 and trunnion members 56.

The pane units 40 are best illustrated in Figures 13, 14 and 17 through 21. Figure 13 shows fragmentarily a pair of adjacent sash 35, 36, including pane units, in order to disclose the operative relationship between such adjacent sash. The pane unit 40 comprises two panes of glass 41, 42 bound together in parallel relation by top and bottom horizontal molding members 43, 44 and vertical molding members 45, the members 43, 44, 45 being of channel construction and each extending in clamping relation along one border portion of the parallel panes 41, 42. Putty 46 extends between panes 41, 42 and between the panes and the molding members.

The horizontal channels or molding members 43, 44 have one side wall 47 of thickened construction, and extending in prolongation thereof beyond the bottom wall 48 of the channel is the lip portion 49.

The end portions of horizontal molding members 43, 44 are formed with recesses 50 extending longitudinally inward therefrom, and a transversely extending slot 51 is formed in the bottom wall 48 of members 43, 44 inward of an adjacent recess 50.

The end portions of side walls 52 of vertical molding members 45 are relieved to form tongues extending into the recesses 50.

The members 43, 44 are preferably extruded products while members 45 are preferably aluminum or magnesium castings. A strip 55 of deformable material such as sheet steel or brass extends into slot 51, thence along bottom wall 48 and in prolongation thereof. In assembling the pane unit, the horizontal members are first applied to the panes, the vertical members are then slid on the panes by sidewise motion which also locks tongues 53 in recesses 50, and the strips 55 are then bent to the full line position of Figure 17 to tie the unit together. The unit evidently may be taken apart very easily for replacement of broken panes.

Sash 35—39 further comprise the trunnion members 56, the latter comprising, preferably cast integrally as illustrated, trunnion 57 and pane frame member 58 of channel construction, extending substantially perpendicularly thereto. Member 58 comprises at its lower end a foot member 59 substantially closing the lower end of the channel and constituting a platform for the support of the pane unit 40. Trunnion 57

is formed with a substantially radial threaded hole 60.

Stile members 31, 32 are substantially rectangular tubular. They comprise an outer wall 61 facing on the outside of the building, an inner wall 62 facing interiorly thereof, a jamb 63 facing into the window opening, and a rear wall 64 opposite the jamb 63 and relieved by a longitudinal opening 65 through which the various members to be mentioned hereafter may be placed inside the stile. Rectangular metal anchor pads 66 span opening 65 at intervals, and anchor screws 67 pass through pads 66 and wall 64 into the wall 68 of the building. Screws 67 and 69, the latter to be described hereafter, are applied by a screwdriver entered through the hole 70 in jamb 63.

Jamb 63 is recessed as at 71 for the entire height adjacent front wall 61 for the reception of a rubber or similarly resilient weatherstrip 72. A lip portion 73 of stile 31 extends in prolongation of the reveal 61A or outer surface of wall 61 and past the plane of jamb 63 into the window opening.

Sash 35-39 are pivoted in stiles 31, 32 on the trunnions 57, the latter being rotatably and slidably supported in bearings 74, 75, the two latter being firmly positioned by their flared necks in walls 64, 63 respectively.

Rocker arm 76 is rotatably and slidably mounted on trunnion 57 between bearings 74, 75. Motion of rocker arm 76 axially of bore 77 by which it is mounted on trunnion 57 is however prevented by the bearings 74, 75 which act as spacers to prevent such motion relative to stile 31, so that relative axial motion between trunnion and rocker arm as described hereafter results in displacement of the trunnion by the rocker arm.

Rocker arm 76 has a body portion 78 formed with the diagonal cam slot 79 extending between lines 80, 81 separated radially and axially of bore 77 and trunnion 57. The pin 82 partially threaded engages threaded hole 60, extending radially from trunnion 57 into slot 79. Rocker arm 76 further comprises the arm portions 83, 84 of similar side elevational contour spaced from each other axially of bore 77 of body portion 78 and integral therewith. Portion 84 is a lever, being threaded to receive the threaded portion 85 of connecting pin screw 69, the latter further comprising the pin portion 86 which extends into the hole 87 of rocker bar 88 thereby pivotally connecting each rocker arm 76 to rocker bar 88. The portion 83 acts as a keeper to prevent rocker bar 88 from slipping off the pin portion 86. In all operative positions of rocker arm and rocker bar, the axis of hole 87 is offset horizontally from the axis of trunnion 57 so that vertical motion of rocker bar 88 results in rocking or rotation of rocker arm 76 about the axis of trunnion 57. Rocker bar 88 is recessed as at 89, Figure 8, so that the rocker bar may partially overlie trunnion 57 as shown in that figure.

Downward motion of rocker bar 88 is accomplished by the cable 90 which is attached to the lower end thereof and led over pulleys 91 in pulley block 92 in sill 34 below stile 31, cable 90 further being led over pulleys 93 in pulley block 94 attached to the lower end of bar 88, cable 90 further extending from pulley block 92 to the window opening pin 95. Cable 96 is similarly disposed relative to corresponding mechanism in stile 32 and is connected to window opening pin 97.

Upward motion of rocker bar 88 is accomplished

by the cable 98 connected to the upper end thereof and led over pulley 99 in sill 34, also over pulley 100 in sill 34 and connected to window closing pin 101. Cable 102 is similarly disposed relative to corresponding mechanism in stile 32 and is connected to window closing pin 103.

Cable actuating mechanism comprises the main shaft 104 set in bearings 105, 106 in sill 34. Bearing 106 is externally threaded and held in place by the nut 107. Pin sleeve 108 is rotatably and slidably mounted on shaft 104 and comprises integrally the pins 109, 110 extending perpendicularly to the axis thereof. Extending diagonally, that is at an angular inclination to the axis of sleeve 108 is the slot 111 and the pin 112 extends radially from shaft 104 into slot 111.

Rotatably and slidably mounted on sleeve 108 are the ratchet drums 113, 114 comprising the drum portions 115, 116 and the ratchet portions 117, 118 respectively. Drums 115, 116 are cylindrical with the exception that they have alternate quarter portions flattened as at 119, 120, 121.

Ratchet drums 113, 114 are identical members comprising ratchet teeth 122 facing counterclockwise of Figure 3, however in operative position as shown in Figure 2 the teeth of ratchet 117 face counterclockwise and those of ratchet 118 face clockwise. Ratchets 117, 118 are each formed with the holes 123, 124 for the reception of the pins 95, 97, 101, 103 respectively. Ratchets 117, 118 are further formed with the rectangular recesses 125, 126 and 127, 128 respectively, for the reception of pins 109, 110 of sleeve 108 as explained hereafter.

The pin disks 129, 130 are identical except for different diameters of the respective central bores 131, 132. Disk 129 is rotatably mounted on the larger diameter 133 of main shaft 104, being positioned against axial movement by bearing 106 and ratchet drum 114, the pins 101, 103, preferably formed integral with disk 129, extending into holes 123, 124 of ratchet drum 114. Disk 130 is rotatably mounted on the smaller diameter 134 of shaft 104, the pins 95, 97 extending into the holes 123, 124 of ratchet drum 113, and disk 130 being locked against axial movement by bearing 105 and ratchet drum 113.

The double pawl 135 is mounted on the pivot shaft 136 between spacers 137 and further fixedly positioned by setscrew 138, pivot shaft 136 being mounted in sill 34 parallel to main shaft 104. The center of gravity of pawl 135 is far to the right of the axis of shaft 136 in Figure 4, so that by gravity the pawl 135 tends to assume a position of engagement of its upper arm 139 with ratchet 117 to prevent counterclockwise rotation thereof. By actuating shaft 136 however pawl 135 may be moved to a position of engagement of its lower arm 140 with ratchet 118 to prevent clockwise rotation thereof.

To operate the window, commencing with the panes in closed and locked position, clockwise rotation of main shaft 104 is first effective to permit gravity disengagement of pawl arm 140 from ratchet 118, slot 111 simultaneously camming pin 112 to move sleeve 108 upward of Figure 5, disengaging pins 109, 110 from ratchet 118 and engaging them with ratchet 117. Window opening pins 95, 97 being permanently engaged therewith, draw cables 90, 96 onto drum 115. These cables, acting over the pulleys 91, 93 and corresponding mechanism in stile 32, draw down rocker bar 88, swinging rocker arm 76 to the right of Figure 8. This is first effective to cam pin 82 and trunnion 57 to the right of Figure

9, moving trunnion member 58 to the right of Figure 9 past weatherstrip lip 73 against the action of leaf spring 141 to unlock and unseal the window.

Further clockwise rotation of shaft 104 and downward motion of rocker bar 88 results in clockwise rotation of trunnions 57 to open the window panes, closing being prevented at any time actuation of shaft 104 ceases by the gravity engagement of arm 139 with ratchet 117.

To close the window, arm 139 is first disengaged by manual actuation of shaft 136 simultaneously with a slight clockwise rotation of main shaft 104, after which partial or total closing is achieved by gravity retarded by suitable clockwise pressure on shaft 104. Arm 139 of pawl 135 will re-engage ratchet 117 as soon as permitted to do so by release of pressure on shaft 136.

To lock the window, shaft 136 being actuated counterclockwise to disengage arm 139, counterclockwise rotation of shaft 104 cams pin 112 to move sleeve 108 downward of Figure 5 to engage pins 109, 110 in ratchet 118, and further counterclockwise rotation of shaft 104 winds cables 98, 102 onto drum 116, the cables being effective over pulleys 99, 100 to raise rocker bar 88 and rocker arm 76 to the position of Figure 8, pin 82 being drawn leftward to the illustrated position of Figure 9 to draw trunnion member 58 into substantially parallel contact with weatherstrip lip 73 and to the rear thereof, locking the window and sealing the same by compressing rubber strip 72, while spring 141 and a corresponding spring in the opposite trunnion member keep the pane unit 40 centered between its trunnion members 58. When the window is locked, arm 140 of pawl 135 is engaged with ratchet 118 by counterclockwise rotation of shaft 136, to prevent rotation of ratchet drum 114.

It will thus be seen that there is provided a device in which the several objects of this invention are achieved, and which is well adapted to meet the conditions of practical use. As various possible embodiments might be made of the above invention, and as various changes might be made in the embodiments above set forth, it is to be understood that all matter herein set forth or shown in the accompanying drawing is to be interpreted as illustrative and not in a limiting sense.

What is claimed is:

1. In a window of the type comprising a pane tilttable about a substantially horizontal axis, the combination with a window frame and a pane tiltably mounted therein on axially slidable trunnions, of a rocker arm pivotally mounted on one of said trunnions within said window frame and fixed against axial movement relative to said frame, said rocker arm being formed with a diagonal slot, a pin mounted in said trunnion and extending into said slot, and means for rotating said rocker arm on said trunnion, whereby said trunnion may be caused first to slide axially in the direction of said pane and then to rotate to tilt said pane from vertical position, opposite rotation of said rocker arm permitting rotation of said trunnion to return said pane to vertical position and then causing opposite axial motion of said trunnion.

2. In a window according to claim 1 and comprising a plurality of sash, said means comprising a rocker bar pivotally connected to the rocker arm of each sash, a cable connected to said rocker bar, a shaft mounted in said frame, said cable being connected to said shaft, and means

for rotating said shaft to draw said cable thereonto.

3. In a window according to claim 1 and comprising a plurality of sash, said means comprising a rocker bar pivotally connected to the rocker arm of each sash, a pulley mounted on said bar, a shaft mounted in said frame, a pulley mounted in a corner of said frame, a cable connected to said bar and led over said pulleys to said shaft and connected thereto, and means for rotating said shaft to draw said cable thereonto.

4. In a window construction according to claim 3, a second cable connected to the opposite end of said bar and to said shaft, and drums concentrically and rotatably mounted on said shaft, said cables being connected to said shaft through said drums, oppositely facing ratchets operatively connected to said drums, means for selectively interengagement of said shaft with either drum for simultaneous rotation, and pawl means selectively engageable with either ratchet.

5. In a window construction according to claim 4, said pawl means being engaged in a position of rest with one of said ratchets and comprising means for manual actuation into engagement with said other ratchet.

6. In a window construction according to claim 1, said means comprising a cable connected to said rocker arm, a shaft mounted in said frame, said cable being connected to said shaft, and means for rotating said shaft to draw said cable thereonto.

7. In a window construction of the type comprising a sash pivotally mounted in a frame for rotation about a substantially horizontal axis, the combination with a window frame and a window pane of a pair of trunnion members each comprising in fixed relation a trunnion and a pane frame member of channel construction extending substantially perpendicularly to said trunnion, said trunnion members being slidably mounted in said frame and being slidable relative to said pane axially of said trunnions, resilient means located in said pane frame members between said trunnion members and said panes, rocker arms pivotally mounted on said trunnions within said window frame and being fixed against axial motion relative to said window frame, said rocker arms being formed with diagonal slots, pins mounted in said trunnions and extending into said slots, and means for causing rotation of said rocker arms.

8. Means for producing successive sliding and tilting motions of trunnions of window panes in windows of the type comprising panes tilttable on substantially horizontal axes, comprising the combination with a window frame stile member of a window pane trunnion revolvably and slidably mounted in said stile member, a rocker arm revolvably mounted on said trunnion and fixed against axial movement relative to said stile member, said rocker arm being formed with a diagonal slot, a pin mounted in said trunnion and extending into said slot, and means for rotating said rocker arm.

9. Cable actuating means for an awning type window of the type comprising a hollow window frame, a sash member pivotally mounted therein, and separate cables operatively connected to said sash member for opening and closing same respectively, the combination of a main shaft rotatably mounted in said frame, separate drums for each of said cables, said drums being rotatably mounted on said shaft and a sleeve slidably and rotatably mounted on said shaft and formed

with a diagonal slot, said sleeve comprising means for selectively engaging either of said drums to rotate same with said sleeve, said shaft further comprising a pin extending into said slot of said sleeve, whereby rotation of said shaft operates first to slide said sleeve into engagement with one of said drums and then to rotate sleeve and drum, and opposite rotation of said shaft slides said sleeve out of engagement with said drum and into engagement with said other drum, and then rotates said sleeve and said other drum. 10
